UNITED STATES PATENT OFFICE.

JOHN HENRY STRICK AND JAMES PROPERT REES, OF NEATH, SOUTH WALES.

MACHINE FOR CLEANING AND BRANNING TIN PLATES AND TERNE PLATES.

1,252,055.

Specification of Letters Patent.

Patented Jan. 1, 1918.

Application filed May 31, 1917. Serial No. 172,133.

To all whom it may concern:

Be it known that we, JOHN HENRY STRICK and JAMES PROPERT REES, subjects of the King of Great Britain, residing at Neath, 5 Glamorganshire, South Wales, Great Britain, have invented certain new and useful Improvements in Machines for Cleaning and Branning Tin Plates and Terne Plates, and of which the following is a specification.

10 This invention relates to improvements in machines for cleaning and branning tin-plates and terneplates preparatory to the dusting of the said plates.

The present invention refers to improvements in such machines of that known type having a trough containing the cleaning material, a rotary carrying member entering the said trough and revolved by suitable means, the rotary member carrying mechanically-operated clips adapted to seize the leading end of a tinplate at one end of the trough and to draw the said plate in tension through the cleaning material in the trough and to release the said plate upon leaving 25 the cleaning material at the opposite end of the trough, and so that if desired the plate can be received by mechanical gripping mechanism carried by a rotary member in a second trough, the plates to be treated being thus held at their forward ends by the gripping mechanism and drawn or trailed through the cleaning material in the trough or troughs.

The present invention refers to the provision of a blade or paddle extending across the trough and being fixed to and carried by the rotary members, and located in advance and adjacent to the clips by which the leading edge of the plate treated is 35 gripped. These paddles consist of blades fixed at any desired angle to the direction of motion, and we have found that the cleaning effect of the machine is improved by the use of such blades or paddles, which latter carry a portion of the cleaning material in front of the plates being treated, and from the paddle the material falls and drifts loosely upon the plates. In combination with such an arrangement we generally 45 provide spring deflecting rods, one end of each of which is rigidly fixed to the rotary carrier near the rear of the mechanical clips by which the forward end of the plate is held, and these spring rods extend rearwardly and support the trailing portion of

the plate, so resiliently holding the plate somewhat eccentric to the center about which the rotary carrier revolves and in a position in which the surface of the said plate advantageously receives the drift of 60 the cleaning material passing from the paddle located in front of the plate; moreover upon the plate leaving one trough, the spring rods cause the free end of said plate to be delivered over the edge of the said 65 trough, which is convenient for the delivery of the plate on to a receiving table or into the clips of the carriers of a second trough.

We will now describe a convenient form and construction of a machine with reference to the accompanying drawings by which the said invention can be carried into effect. Figure 1 is an elevation, part of which is in section, of a machine as aforesaid, and Fig. 2 is a right hand sectional end 75 view of the same.

Referring to the drawings, an open-topped trough 1 is provided, having a revoluble shaft 2 extending through it and carried in bearings 3 in the ends of the 80 trough, and the shaft is revolved in the direction of the arrow Fig. 1 by any suitable means, such as by a toothed wheel 4 mounted on the shaft 2, gearing with a pinion 5 on a shaft 6 driven by a pulley 7 85 from any prime mover. The interior of the trough 1 is curved after the manner indicated in the trough on the left hand side of Fig. 1, hereafter referred to, the curvature being concentric with the axis of the shaft 2. 90

The shaft 2 has fixed upon it a plurality of skeleton disks or wheels, hereafter termed carriers 8, these carriers entering the trough 1 and being of such diameter that their peripheries are at a suitable distance from the 95 interior surface of the trough.

Each carrier 8 carries one, or as shown a plurality, of spring clips, each of these clips consisting of a radial rod 9 suitably guided as at 10 by a pin on the carrier passing 100 through a slot in the rod, and the rod 9 has a foot 11 which extends over the periphery of the carrier, while a spring 12 on the rod of the clip acting between a nut on the rod and a lug 13 on the carrier, holds the foot 105 11 in contact with the periphery of the carrier; the radial rod 9 on one carrier is in line with the similar radial rods of the clips on the other carriers, and a bar 14, Figs. 1 and 2, extends through the spaces in the 110

carriers 8 and is fixed to each radial rod 9, and such a bar 14 we term a touch rod.

Fixed to the trough, one upon each side thereof, are two frames 15, each of which 5 carries an adjustable cam surface 16, and also fixed within the trough there are two cam surfaces 17 one at each side thereon, these cam surfaces 16 and 17 being for the purpose of acting at proper times upon the 10 radial rods 9 in order to distance the feet 11 of the rods 9 from the periphery of the carriers 8 to release a plate, and also to distance the radial rods 9 from the periphery of the carriers at proper times to receive a plate.

15 With mechanism thus far described, as the carriers 8 revolve and as one of the touch rods 14 enters the feed side of the trough, the ends of the said touch rod 14 contact with the fixed cam surfaces 17, whereby the 20 radial rods 9 connected with that particular touch rod, are moved radially outward and the feet 11 of the clip are distanced from the peripheries of the carriers, so that the tin or terneplate or plates, hereinafter termed 25 tinplate, can be inserted between the feet 11 of the clips and the peripheries of the carriers 8, so that the tinplate is immediately gripped as soon as the ends of the touch rods pass away from the cam surfaces 17. 30 Thereafter during the further revoluble motion of the carriers the tinplate is drawn through the cleaning material in the trough, in tension.

35 The tinplate marked 18 on the right hand side of the drawing Fig. 1, which is the feed end of the machine, is fed in between suitable guides 19 so that the lower edge of the plate 18 rests on a stop plate 20 fixed on a rock shaft 21 to which tappet levers 22 are 40 fixed, counterweighted at 23 and maintained in the position shown by a stop arm 24 on the shaft 21.

On the outer carriers are laterally extending pins 25, Figs. 1 and 2, which rock the levers 22 as they pass, and tilt the stop plate 20 so that the tin plate 18 slides into the jaws of the carrier clips. The tinplate is then drawn through the cleaning material in the trough 1, and as it leaves the cleaning material 45 the touch rod of the set of clips contacts with the cam surfaces 16 carried by the frames 15, and the tinplate is released and can be guided onto a table or into a dusting machine as desired.

50 Carried from the periphery of the carriers are the blades or paddles which form one of the features of the invention.

The paddles marked 26 in the drawings are located and fixed at or near the peripheries of the carriers and extend parallel with the shaft 2 thereof; each paddle comprises a plate 26 extending across the machine and fixed by brackets 27 to the carriers, the said paddle being located in advance and adjacent to each set of clips, the purpose of these

paddles being to carry a portion of the cleaning material in front of the plates, and from which paddle the material falls or drifts loosely on the plates.

Coacting with each clip on a carrier is a 70 spring deflecting rod 28 comprising a resilient rod or wire, one end of which is rigidly fixed to the face of its carrier at the rear of a clip, while the opposite free end (the rod 28 being curved) normally stands beyond 75 the periphery of the carrier so that the tinplate, when gripped by the clips, will have its position defined by resting on the deflecting rods 28.

It will now be understood from the foregoing description that a tinplate on the right hand side of the drawing Fig. 1 having been passed into the clips, is gripped thereby at its entering end and is drawn through the trough while it is supported by the deflecting rods 28; and having so passed through the trough, the free end of the plate is held out away from the carriers by the action of the deflecting rods 28, the plate is then released from the clips and upon release it is 90 free to pass away clear of the trough.

Such a machine generally consists of more than one trough, the drawing Fig. 1 showing two exactly similar troughs working in conjunction, the shaft 2 of one trough being 95 parallel with the shaft 2 of the other trough, with the adjacent edges of the two troughs in contact, and when so arranged, the tinplates which are inserted in the spring clips at the feed end of the first trough are drawn 100 through the cleaning material in the first trough and carried out of that material so that the lower edges of the tinplates are above the edge of the first trough on the delivery side; and then the touch rod of a set 105 of spring clips, holding the plates, contacts with the cam surfaces carried by the bridge pieces and the plates are released, and guided by the ends of the spring deflecting rods 28 they become received by a set of similar 110 spring clips of the second trough, which spring clips are at that moment in an open position, their touch rods contacting with the cam surfaces fixed in the entrance end of the second trough. The plates are then 115 drawn through the second trough and similarly delivered at the delivery end of the second trough on to a bench or into a dusting machine as desired.

What we claim as our invention and desire to secure by Letters Patent is:—

1. In machines of the kind hereinbefore specified for cleaning and branning tinplates and terneplates; the combination therewith of a blade consisting of a blade extending 125 across the trough containing the cleaning material, and means for fixing said blade to the rotary carrying members in advance of and adjacent to the clips which grip the leading end of the plate, to carry and dis- 130

turb the cleaning material in said trough in advance of the leading end of said plate being cleaned.

2. In machines of the kind hereinbefore specified for cleaning and branning tinplates and terneplates; the combination therewith of paddles each consisting of a blade, one of said blades being located in advance of each set of the clips for gripping the leading ends of the plates to be cleaned, said blades extending across the trough parallel with the shaft of the carrying members, and means for fixing said blades to said carrying members near the peripheries thereof to carry and disturb the cleaning material in the trough in advance of the leading ends of the plates gripped by said clips.

3. In machines of the kind hereinbefore specified for cleaning and branning tinplates and terneplates; the combination therewith of paddles each consisting of a blade, one of said blades being located in advance of each set of the clips for gripping the leading ends of the plates to be cleaned, said blades extending across the trough parallel with the shaft of the carrying members, and means for fixing said blades to said carrying members near the peripheries thereof with the surfaces of said blades at an angle to the direction of motion to carry and disturb the cleaning material in the trough in advance of the leading ends of the plates gripped by said clips.

4. In machines of the kind hereinbefore specified for cleaning and branning tinplates and terneplates; the combination therewith of a paddle consisting of a blade extending across the trough containing the cleaning material, means for fixing said blade to the rotary carrying member in advance of and adjacent to the clips which grip the leading end of the plate, to carry and disturb the cleaning material in said trough in advance of the leading end of said plate being cleaned, spring deflecting rods, and means for rigidly fixing one end of each of said rods to the rotary carrying members near to and rearward of said clips, said rods ex-

tending rearwardly of said clips and eccentrically to the axis of said carrying members with the rearward free ends of said deflecting rods supporting the trailing portion of the plates and resiliently holding same eccentric to the center about which the carrying members revolve.

5. In machines of the kind hereinbefore specified for cleaning and branning tinplates and terneplates having a plurality of troughs to contain the cleaning material located end to end and adjacent to each other, rotary carrying members entering each trough, means for revolving each set of carrying members, clips carried by each set of carrying members, and means for operating said clips to grip the leading end of a tinplate at one end of one trough to draw said plate through the cleaning material and to release same upon leaving the other end of the trough; the combination therewith of spring deflecting rods on said carrying members fixed near to and extending rearward of said clips, said deflecting rods extending eccentrically to the axis of said carrying members to resiliently hold the plates eccentric to the center about which the carrying members revolve and calculated as the trailing end of each plate leaves the delivery end of the first trough to throw said end of said plate forward into the next trough, paddles each consisting of a blade, and means for fixing said blades near the peripheries of said carrying members so that said blades extend across said trough parallel with said shaft one of said blades being located forward of each set of clips to carry and disturb the cleaning material in said trough in advance of the leading end of said plate.

In witness whereof we have hereunto set our hands in the presence of two witnesses.
